Attorneys,

UNITED STATES PATENT OFFICE.

JAMES W. JORDAN, OF ZACH, TENNESSEE.

RAILWAY-TIE.

1,367,265.

Specification of Letters Patent. Patented Feb. 1, 1921.

Application filed December 10, 1920. Serial No. 429,714.

To all whom it may concern:

Be it known that I, JAMES W. JORDAN, a citizen of the United States, residing at Zach, in the county of Benton and State of Tennessee, have invented new and useful Railway-Ties, of which the following is a specification.

This invention relates to railway ties, one of its objects being to provide a metallic tie so constructed that it will not creep upon the roadbed after being properly placed in position, and which is free to flex or yield under the weight of cars passing thereover, thereby to provide an elasticity corresponding with that afforded by the use of ordinary wooden ties.

A further object is to provide a railway tie made up of detachably connected sections anyone of which can be replaced readily by a new section in the event of wear or breakage.

Another object is to provide simple and efficient means for connecting the sections of the tie.

25 A still further object is to provide novel means for securing rails to the tie.

With the foregoing and other objects in view which will appear as the description proceeds the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

40 In said drawings—

Figure 1 is an elevation of the tie, rails being shown in position thereon.

Fig. 2 is a plan view of one end portion of the tie.

45 Fig. 3 is a section on line 3—3, Fig. 2.

Fig. 4 is a section on line 4—4, Fig. 1.

Referring to the figures by characters of reference 1 designates end sections of the tie and 2 designates an intermediate section, these sections being preferably cast of metal and bowed or arched transversely to provide a bottom channel shown at 3 whereby the material of the roadbed can be tamped into the channels as well as along 50 the sides of the sections, thus to prevent the

tie from creeping. The sections are placed end to end as shown and secured in any suitable manner to the top of the intermediate section is an elongated metal strip 4 preferably of steel designed to lap the inner ends 60 of the sections 1 and provided at its free ends with tongues 5 which are undercut as shown in Fig. 3 so as to be spaced from the top surfaces of the sections 1. Transverse dove-tails 6 are formed on the bottom 65 face of the strip 4 near the tongues 5 and formed within the upper surface of each of the sections 1 are transverse dove-tailed grooves 7 designed to receive the dove-tails 6, thereby to hold the sections 1 and 2 70 properly assembled. After the dove-tails have been seated in the grooves they can be held against withdrawal therefrom by means of bolts 8 arranged in pairs and extending upwardly from the sections 1. Each 75 tongue 5 extends between the bolts of one pair and is held down between said bolts by a cross strip 9 secured to the bolts.

Suitably secured to the sections 1 are rail fastening blocks 10 which preferably engage the under surfaces of the outer sides of the heads of the rails R, these blocks being properly spaced apart so that when the rails are in engagement therewith they will be held in proper relation and cannot spread. 80 Additional rail engaging members 11 are mounted on the end members 1 and have openings 12 extending therethrough into which the tongues 5 project. These members 11 are slidable on the tongues and carry 85 set screws 13 which can be adjusted into engagement with the tongues so as to hold the members 11 in any positions to which they may be moved. Thus it will be seen that after the rails have been positioned against 90 the members 10 the members 11 can be moved against the inner sides of the rails and then fastened.

What is claimed is:—

1. A metallic railway tie including separate alining end and intermediate sections, a resilient strip detachably connecting said sections and separate means upon the end sections and the resilient strips respectively for fastening rails to the end sections. 100

2. A metallic railway tie including separate alining end and intermediate sections, a resilient member mounted on and detachably connecting said sections, rail engaging members upon the end sections, and means 105 110

adjustably mounted on the resilient member for engaging and fastening rails upon the end sections.

3. A metallic railway tie including an intermediate section, a resilient strip upon and secured to said section and projecting beyond the ends thereof, end sections detachably engaging and lapped by the end portions of said strip, and coöperating means upon the end sections and the end portions of the strip respectively for fastening rails to the end sections.

4. A metallic railway tie including an intermediate section, a resilient strip secured thereto and projecting beyond the ends thereof, end sections slideable transversely into engagement with the resilient strip, and rail fastening means upon the end sections.

5. A metallic railway tie including an intermediate section, a flexible strip secured to and projecting beyond the ends of said

section, end sections movable transversely into engagement with the strip, said sections and strip having coöperating means for holding them assembled, and means upon the end sections for engaging the strip to hold them against relative transverse movement.

6. A metallic railway tie including flexibly connected sections, rail engaging means fixedly secured to certain of the sections, tongues spaced from said certain sections and connected thereto, and rail engaging means adjustably mounted on the tongues.

In testimony that I claim the foregoing as my own, I have hereto affixed my signature in the presence of two witnesses.

JAMES W. JORDAN.
